Primary Examiner — Terry Wallace(74) Attorney, Agent, or Firm — Florek & Endres PLLC(57) CLAIM

We claim the ornamental design for a bowl with lid, as shown and described.

DESCRIPTION

FIG. 1 is a perspective view of the bowl with lid of the present invention.

FIG. 2 is a front elevation view of the bowl with lid of the present invention.

FIG. 3 is a rear elevation view of the bowl with lid of the present invention.

FIG. 4 is a left side elevation view of the bowl with lid of the present invention.

FIG. 5 is a right side elevation view of the bowl with lid of the present invention.

FIG. 6 is a top plan view of the bowl with lid of the present invention; and,

FIG. 7 is a bottom plan view of the bowl with lid of the present invention.

The broken lines in the drawings represent unclaimed features.
